UNITED STATES PATENT OFFICE

104,030

DESIGN FOR A REFLECTOR

Arcadius Gunsbourg, Brussels, Belgium

Application July 7, 1936, Serial No. 63,689

Term of patent 14 years

To all whom it may concern:

Be it known that I, Arcadius Gunsbourg, a citizen of the Lithuanian Republic, residing at 45, Rue du Pépin, Brussels, Belgium, have invented a new, original, and ornamental Design for Reflectors, of which the following is a specification, reference being had to the accompanying drawing, forming part thereof.

Fig. 1 is a perspective view of a reflector, showing my new design; and

Fig. 2 is a sectional view taken on line II—II of Fig. 1.

The design is characterized by a circular body provided on its outer surface with downwardly extending and concentrically disposed prismatic faceted areas, the body being surmounted by a collar adapted to fit over a lamp bulb.

I claim:

The ornamental design for a reflector substantially as shown and described.

A. GUNSBOURG.
